UNITED STATES PATENT OFFICE.

RUSSELL PLATO SCHWARTZ, OF CINCINNATI, OHIO.

ELECTRODE-HOLDING DEVICE.

Application filed July 6, 1926. Serial No. 120,665.

My invention relates to the general class of electrode holding devices and particularly to devices for supporting a plurality of carbon electrodes from which rays are projected for projecting rays at their maximum intensity on any desired object.

It is the object of my invention to provide an easily adjustable bracket for supporting carbon electrodes or other ray projecting electrodes, which project a maximum of rays at angles to the meeting ends of the electrodes. Further it is my object to provide an adjustable bracket which will with slight readjustment increase the dimensions of the circular area in which the greatest scope of radiation occurs thereby increasing the range of exposure to the rays in a circle about the holding device or increasing the angle of inclination of the bodies of the patients or the other objects which are to receive radiation.

For the treatment of patients having many different diseases, I have found great difficulty in subjecting their bodies to the rays from electrodes, and at the same time providing for their comfortable reclining in positions at proper angles to the electrodes in which position they will be within the area of maximum radiation. I have found that with my bracket structure which will be hereinafter described and claimed I am able to comfortably dispose a number of patients in reclining position with their bodies at approximate right angles to the alignment of the ray projecting electrodes. By a simple adjustment of the bracket I am further able to increase the number of patients or articles being exposed to radiation by decreasing the apex angle of the inverted cone in which the electrodes are retained so that the rays, which are projected at maximum intensity at approximate right angles to the slant height of the cone will circumscribe a circle of greater circumference and more patients or articles may be subjected to radiation.

Referring to the drawings in which I have illustrated my preferred bracket construction:

Figure 1 is a detail section of one arm of the bracket as indicated by the lines 1—1 in Fig. 2.

Figure 2 is a perspective view of the complete assembly of holder and electrodes.

Figure 3 is a diagram of an imaginary

section of electrodes and patients or articles illustrating the geometrical principle involved.

Generally indicated at 1 is a vertical suspended sleeve which may conveniently be rigidly secured in the ceiling of the room in which patients are to be treated or may be suspended from a chain or cable so that by passing the cable over a pulley the bracket may be drawn to the floor for re-adjustment.

An upper spider 2 is mounted on the sleeve by a bushing 3 and forms a convenient mounting for a fixed or slideable support. A lower spider 4 is fixedly mounted on the sleeve at the lower end thereof. Between the spiders on the rod the solenoids 5 are suspended from the spider by springs 5^a.

Trunnion shaped bosses 6 extend from the upper spider and pulleys 7 are pivotally mounted in the bosses. The lower spider is likewise provided with bosses which pivotally mount links 8. Each set of links has an aperture at 9 through which cables 9^a are secured. The cables pass over the pulleys 7 and extend to a member 9^b which projects from the bottom of the sleeve and is provided with an adjustment collar 10. Thus the links 8 are held in the line of the slant height of an inverted cone. A handle 10^a at the lower end of the member 9^b provides a simple means of adjusting the angle in which the electrodes are held. As the links 8 are held in alignment with the slant height of an inverted cone, as the handle 10^a is moved downward as illustrated in Figure 1, the angle of the apex of the cone will be increased and an imaginary circle described at right angles to the slant height of the cone will have a decreased circumferential area.

The electrodes which in the illustration are high power carbon electrodes are secured on the links 8. In the illustration I have shown four sets of links, but it will be understood that greater or less number of links may be used as long as they are held in alignment with the slant height of a cone. The electrodes are supported in the usual manner, the lower electrodes being stationary, and the upper ones held at sufficient distance from the lower ones to permit a suitable arc. Solenoids 5 suspended from the spider 2 are adapted to magnetize armatures 12 to which are secured chains 13.

The chains pass over pulleys 14 and are secured at the ends to negative electrode holder plates 15. When the current is turned on through the solenoids the armatures are drawn up and the chains pull on tubular portions 16 in which the negative electrodes are mounted. In this way the carbon points are kept with a sufficient gap between them to form a silent arc.

10 I have found that by suspending the solenoid casing from springs a much more delicate adjustment is provided for the tension of the electrode holder plates and hissing and sparking is thereby eliminated. The armatures 12 may be suspended from a rod which extends up through the casing into a closed cylinder in which it is attached to a piston so that a dash pot effect is provided which has been found to provide a 20 very effective and delicately balanced mechanism.

Preferably the positive carbon electrodes 17 are supported in projections 18 which extend from the links 8 spider. In the use of a high powered arc in which the electrodes are surrounded by a copper casing 17^a I have found that by disposing the positive electrode below the negative not only is there no tendency for the copper casing to melt and 30 be sprayed off, but the greater the angle of the links 8, the more the crater of the positive electrode tends to project a maximum of rays downwardly.

The patients or articles to be subjected to radiation are disposed in a circle approximately at right angles to the positions in which the electrodes are retained. In the diagram Figure 3 it will be observed that as the angle at the apex of the cone in which the electrodes are disposed is decreased, the spread of the circumference of a circle in which rays projected at approximately right angles to the slant height of the inverted cone will be increased. This forms a convenient way for providing radiation for a variable number of patients or articles in the circle below the carbon electrodes, or in the case of patients it allows their bodies to be raised from a lying position to a sitting position as indicated by the change in the dia-grammatical positions indicated at 19 and 19^a.

Although my holding device for electrodes is particularly adapted for the treatment of sick people the apparatus is also suitable for the effective treatment of growing vegetation and for a great variety of purposes in which it is desired to vary the effective scope of rays projected from electrodes.

60 Having thus described my invention, what I claim as new and desire to secure by Letters Patents, is:

1. In combination with a holder, a plurality of sets of electrodes, said electrodes mounted so as to project rays of maximum

intensity at acute angles to the vertical, and means of adjusting the electrode mountings so as to change the angles to the vertical of the rays projected from the electrodes.

2. A holder for a plurality of units consisting of a positive and a negative electrode units of electrodes mounted on said holder, said electrodes adapted to project rays at maximum intensity at angles to the lines in which they are disposed, said electrodes disposed on lines of the slant height of an inverted cone whereby the rays from said units project circumferentially in a circle, and means of varying the slant height of the cone in which said units are disposed. 70 75 80

3. A holder for a plurality of units consisting of a positive and a negative electrode, electrodes mounted in said holder, said electrodes adapted to project rays at maximum intensity at angles to the lines in which they are disposed, said series of electrodes disposed on lines of the slant height of an inverted cone whereby the rays from said units will project in the circumference of a circle, and means for adjusting the holder to increase and decrease the circumferential area into which the rays are projected. 85 90 20

4. A holding device comprising a central sleeve, a spider mounted on the sleeve, solenoids suspended from said spider, a fixed member mounted on said sleeve having a plurality of links articulated thereto, said links with ends pivotally secured to said fixed member, and said links secured to the fixed member having electrodes thereon, said electrodes disposed in alignment with the slant height of an inverted cone, said solenoids adapted to control the arcs between said electrodes, and adjustable means for varying the projecting angle of rays projected at maximum intensity at angles to the electrodes. 100 105

5. An electrode holding device comprising a central sleeve, a spider mounted on the rod, solenoids suspended from said spider, a fixed member mounted on said sleeve having a plurality of links articulated thereto, said links carrying ray projecting electrodes, said electrodes disposed in alignment with the slant height of an inverted cone, said solenoids for controlling the arcs of said electrodes, adjustable means for varying the projecting angle of rays projected at angles to said electrodes, said means adapted to regulate the projection of the rays within the circumference of circles varying from a circle formed by rays projecting downward in alignment with the mounting sleeve and a circle extended at right angles to the mounting sleeve. 110 115 120

6. In a holder a plurality of units of ray projecting electrodes, units of electrodes adapted to project a maximum intensity of rays within a circular area extended approximately at right angles from the elec- 125 130

trodes, and adjustable means of moving the angles of said series coincidentally in order to vary the angle at which said rays are projected.

5 7. In combination with a holder, a plurality of units of ray projecting electrodes mounted at an acute angle to the vertical, and means of varying the angle of the electrodes of all of said units simultaneously.

10 8. In an electrode holder, a series of electrodes arranged along lines of the slant height of an inverted cone, positive electrodes disposed below negative electrodes in said series, means of controlling the movement of said negative electrodes with relation to said positive electrodes, and means

15 of varying the slant height of the cone in which said series is disposed.

9. In an electrode holder, a series of electrodes arranged along lines of the slant height of an inverted cone, positive electrodes disposed below negative electrodes in said series, means of moving said negative electrodes with relation to said positive electrodes, and means of varying the slant height 20 of the cone in which said series is disposed, said controlling means comprising solenoid coils with armatures disposed on rods, and resilient means of counterbalancing the magnetic effect of said solenoids on said negative electrodes. 25
